UNITED STATES PATENT OFFICE.

JONATHAN JONES, CHANDLER D. FAULKNER, FRANCIS L. JONES, AND HORACE K. FAULKNER, OF UTICA, NEW YORK.

IMPROVEMENT IN CHEESE-VATS.

Specification forming part of Letters Patent No. 123,107, dated January 30, 1872.

SPECIFICATION.

We, JONATHAN JONES, CHANDLER D. FAULKNER, FRANCIS L. JONES, and HORACE K. FAULKNER, residents of Utica, Oneida county, and State of New York, respectfully represent that we have invented a new and useful Arrangement of Stationary Steam-Pipes for the equal diffusion of steam in vats used in the manufacture of cheese, the same being an improvement on the arrangement of movable steam-pipes patented by E. H. and W. A. Stuart, February 21, 1871, and reissued June 6, 1871. We therefore ask that Letters Patent may be granted us for the same, reference being had to the drawing and figures marked thereon forming a part of this specification.

To enable others skilled in the art to which our invention belongs to manufacture and use the same, we will proceed to describe its construction and operation.

Figure 1 is the outside vat, constructed of wood, to be lined with metal, if desired, of sufficient strength to withstand a pressure of three or four tons' weight. Fig. 2 is the inner vat, to be made of tin or other metal attached to a wooden frame at the top, the under side of which forms a flange to cover the outside vat, making a perfect joint to prevent the escape of steam, which we intend to use for the purpose of warming milk and making into cheese.

The vat, when so constructed, is intended to have a space or steam-chamber between the two vats on each side, end, and bottom of about one and a half inches. Our invention consists in introducing into this chamber steam in such a way that the warmth will be gradual and an equal diffusion throughout the chamber be obtained without having the steam-jet come in direct contact with the inner milk-vat, thus avoiding the scorching of the milk, which always gives the cheese a burned flavor, also injuring the inner metallic vat.

For the purpose of gradually and equally warming the milk, we use two stationary metallic pipes half an inch in diameter, more or less, according to the size of the vat, one above the other on each side of the vat or chamber, making four pipes in all, with cross connections at the ends, and all uniting in one pipe which connects with the boiler. These pipes have holes drilled in them in a straight line of about one-sixteenth of an inch in diameter and eight inches apart, more or less, the holes in the upper pipes being in the top and in the lower pipes on the side. The lower pipes throw jets of steam horizontally toward each other under the inside vat, thus preventing the direct contact of the steam with the inside milk-vat. The steam from the upper pipe on either side is thrown up through the holes in the top perpendicularly, thereby avoiding direct contact with the inside milk-vat. Thus the steam issuing from all the pipes at once fills both sides, bottom, and all parts of the steam-chamber at the same time gently and equally, the quantity being regulated by common steam-valves.

Claim.

What we claim as new, and wish to secure by Letters Patent, is—

The arrangement of the double stationary perforated steam-pipes A A, B B, as herein described, the pipes A A perforated at the top and the pipes B B at the sides, by which steam may be admitted solely at the two sides of the milk receptacle, or solely at the bottom, or simultaneously at both sides and bottom, substantially as specified and set forth.

JONATHAN JONES.
CHANDLER D. FAULKNER.
